CLAIM

(57) The ornamental design for a keepsake book for baby teeth, as shown and described.

DESCRIPTION

FIG. 1 is a perspective view of a keepsake book for baby teeth, showing my new design;

FIG. 2 is a front elevational view of the invention;

FIG. 3 is a rear elevational view of the invention;

FIG. 4 is a left-side elevational view of the invention;

FIG. 5 is a right-side elevational view of the invention;

FIG. 6 is a top plan view of the invention; and,

FIG. 7 is a bottom plan view of the invention.

The broken lines shown in the drawings represent unclaimed portions of the keepsake book for baby teeth and form no part of the claimed design.
